NETTING NEEDLE

Otto H. von Bargen, Duthie, Idaho

Application March 16, 1935, Serial No. 11,444
Renewed September 8, 1936

1 Claim. (Cl. 96—21)

My present invention relates to improvements in netting needles adapted to be employed in fashioning reticulated fabrics, such as fish seines, tennis nets, and net work of a like nature, including doilies, throws, spreads, table covers, heat pads, and various forms of netted or reticulated art work.

It is the object of this invention to provide such a needle having at its opposite ends elements whereby the cord or thread which is being manipulated may be held upon the needle and caught thereon and from which it may be taken during the operation of forming the work upon which it is used.

15 Another object of the invention is to provide a netting needle which may be readily introduced into the fabric of a seine net or other formation and readily removed therefrom, without tearing or injuring the fabric.

20 Another object of the invention is to construct a needle of the character above described from a single piece of material, the resulting article being simple in construction, inexpensive to manufacture, and durable in operation, as well as double-pointed for use at either end.

The invention consists in certain novel combinations and arrangements of parts for accomplishing the above steps and in making the necessary ties and knots, as will be hereinafter more 25 fully pointed out and claimed.

In the accompanying drawing I have illustrated one complete example of the physical embodiment of my invention, but it will be understood that various changes and alterations are 30 contemplated and may be made to suit different conditions.

Figure 1 is a plan view of a portion of a netted fabric, showing on the left hand side, the juxtaposition of a number of strands of yarn or cords 35 utilized in making a pad or cover and, on the right hand side of this same figure, the members are shown tied at their intersections to form a substantial netted fabric.

Figure 2 is a perspective view of the netting needle and Figure 3 is a plan view of a slightly 40 different arrangement.

In carrying out my invention, the needle comprises a body or shank 10 at the ends of which are located spaced, curved prongs 11 and 12 forming a crotch 13 between the prongs. The prongs are of different lengths, the prong 11 being shorter than the prong 12 and curved inward to

underlap the prong 12 which extends beyond the prong 11 and over-rides this prong, forming a substantial point for the needle and being sharpened as at 14 so that it can be used as a pick in loosening or manipulating the cord or thread in case of an improperly tied knot.

The shank 10 is pierced as at 15 and formed with opposed tapered slots 16 which are split at their ends 17 to hold the end of a cord or thread which is later wound upon the needle by wrapping so that the cord will pass between the ends of the prongs and rest in the crotch 13 on the ends of the needle. The needle may be made of any suitable material, either rigid or flexible, such as ebonite, celluloid, sheet metal, or any of the various forms of material that will readily lend itself to stamping or similar formation.

The sizes will be determined by the needs, as obviously, for use in the mending, repair, or manufacture of seines or fish nets, a size having a capacity for carrying considerable cord will be desirable, whereas for finer needle or art work a comparatively smaller sized needle would be more in keeping.

It is intended that all edges will be carefully rounded and formed so as to offer as little friction as possible upon the work during manipulation.

With the formation of my needle, as above pointed out, I have a double-ended instrument at all times adaptable for use in the most convenient manner and without changing end for end when need requires.

I have shown in Figure 2 one form in which prongs at the ends of the needle are formed in reverse order, that is, on opposite sides of the shank portion while in Figure 3 I have shown the shorter prongs on the one side and the longer prongs on the other side of the shank. Either form is readily adaptable for use and for the intended purpose.

Having thus fully described my invention, what I claim as new and desire to secure by Letters Patent is:—

An integral netting needle comprising a flat shank formed with an elongated thread-retaining slot adapted at either end to grip the thread, a bifurcated end forming an enlarged recess and a narrow opening therefrom, said end comprising outwardly bowed prongs with their free ends curving inwardly, and one of said prongs being of greater length than the other prong and overlapping said prong.

OTTO H. von BARGEN.
